UNITED STATES PATENT OFFICE.

HARRY H. SCHROYER, OF CHICAGO, ILLINOIS, ASSIGNOR TO DUNBAR MANUFACTURING COMPANY, A CORPORATION OF ILLINOIS.

AWNING.

1,243,988.

Specification of Letters Patent. Patented Oct. 23, 1917.

Application filed November 26, 1915. Serial No. 63,527.

To all whom it may concern:

Be it known that I, HARRY H. SCHROYER, a citizen of the United States, and a resident of the city of Chicago, in the county of Cook 5 and State of Illinois, have invented certain new and useful Improvements in Awnings; and I do hereby declare that the following is a full, clear, and exact description of the same, reference being had to the accompanying drawings, and to the numerals of reference marked thereon, which form a part of this specification.

This invention relates to an improved type of adjustable awning capable of being rolled 15 up out of use into a comparatively inconspicuous position.

It is an object therefore of this invention to construct an awning wherein the fabric is connected upon a spring actuated winding 20 roller and, when drawn downwardly, is extended by suitable mechanism in a position to shade a window on which the same is attached.

It is also an object of this invention to 25 construct an awning wherein the fabric is connected upon a spring actuated winding roller and is capable of extension into a position to shade a window by mechanisms having sliding engagement with guides connected upon the window frame.

It is also an object of this invention to construct a spring roller type of awning provided with an extending frame for the fabric, slidably mounted in guides on the 35 window frame and when in lowered extended position capable of swinging downwardly but prevented from sliding upwardly in the guides unless first elevated substantially into the plane thereof.

40 It is furthermore an important object of this invention to provide an awning wherein the fabric is adapted to be rolled upwardly into an inconspicuous position at the upper end of the window frame, said fabric having attached thereto mechanisms having sliding 45 engagement with guides on the window frame to extend the fabric and shade the window and with a releasable retaining rod or bar mounted transversely of the window frame to confine one part of the fabric inwardly to effectually and efficiently shade the window.

50 It is finally an object of this invention to construct a simple and improved type of awning easy to operate and consisting of

few parts easily connected upon a window and serving efficiently to shade the window.

The invention (in a preferred form) is illustrated in the drawings and hereinafter more fully described.

60 In the drawings:

Figure 1 is a front face view of a window partly broken away showing the same equipped with an awning embodying the principles of my invention.

Fig. 2 is a central vertical section taken therethrough with parts shown in elevation.

Fig. 3 is a fragmentary detail view in elevation of the retaining rod detachably connected at the middle of the window 70 frame.

Fig. 4 is a detail section taken on line 4—4 of Fig. 3.

Fig. 5 is a fragmentary enlarged sectional detail with parts shown in elevation, taken 75 on line 5—5 of Fig. 2.

Fig. 6 is a detail sectional view with parts in elevation taken on line 6—6 of Fig. 5.

Fig. 7 is a sectional detail with parts omitted and parts in elevation, taken on 80 line 7—7 of Fig. 6.

Fig. 8 is an enlarged detail view illustrating a locking means for the detachable cross rod at the middle of the window frame.

As shown in the drawings:

85 The reference numeral 1, indicates as a whole the window frame, in which are slidably mounted the upper and lower window sashes 2 and 3, respectively. Secured in any suitable manner upon the upright side members of the frame 1, are angle irons 4, which have brazed, riveted or secured thereto in any suitable manner guide channels 5. Mounted at the upper end of the window frame on each side thereof are brackets 6, 90 which receive engaged detachably therein the gudgeon ends of a spring roller 7, to which the edge of the awning fabric, denoted as a whole by the reference numeral 8, is attached and adapted to be wound 95 thereon. Connected at the other or lower end of the fabric 8, is a U-shaped extending bar or bracket 9, having secured upon the inwardly directed arms thereof end caps 10, each of which has formed integral and at 100 right angles therewith a gudgeon head 11, with one side thereof cut away leaving a head of segment shape, as clearly shown in Fig. 6.

105 Said segment shaped gudgeon heads 11, 110

fit within the channels 5, and are adapted to slide therein when the awning is raised and lowered, and secured within said guide channels 5, at the lower end thereof are Z- or angle-shaped brackets 12, each having a bent portion 13, beneath which one side of the segment heads 11, projects, when the U-shaped bracket 9, is swung downwardly into a horizontal position. Due to the shape of the gudgeon heads 11, and position of the bent portions 13, elevation of the gudgeon heads 11, in the guide channels is prevented with the bracket in extended position for use, or even if the bracket is swung downwardly below a horizontal. A controlling and actuating cord 14, is connected at one of its ends to cords 15, which are attached around the roller 7, and at its other end extends through a small pulley 16, secured 20 on the window sill, and with the other end adapted to be engaged over a hook 17, provided on the U-bracket 9, as clearly shown in Figs. 1 and 2, and then attached to any suitable fastening means on the window sill. 25 Said cord 14, thus serves to hold the awning extended, and even accidental release of the spring in the roller 7, so that the same tends to rotate the roller, will be resisted by the cord which is attached around the 30 hook 17.

An angled bracket plate 18, is mounted on the window frame, or if desired attached on one of the guide channels 5, and is provided with an aperture to receive pivotally 35 engaged therethrough a hook 19, which is integral with an end cap member in which a brace or cross rod 20, with its free end bent at an angle, is secured. A notched bracket plate 21, is secured on the opposite side of the window from said plate 18, and is adapted to receive the end of said rod 20, seated therein. A pivotally mounted gravity acting retaining pawl 22, is mounted on said plate 21, acting normally 40 to lock the end of said rod 20, therein, and acting to wedge said rod more tightly in the notched plate 21, if there is a tendency for the rod to be swung up without first releasing the pawl. When swung upwardly 45 into the dotted line position shown in Fig. 8, the pawl permits retraction of the end of said rod 20, from the notched plate, so that said rod may swing downwardly alongside of the window frame in a position out of 50 use, as, for instance, during cleaning of the windows.

The operation is as follows:

The guide channels 5, are first attached to the side frame members of the window 1, and then the brackets 6, in which the roller 7, is detachably journaled. The gudgeon heads 11, of the U-bracket 9, are then engaged through the open ends of the guide channels 5, within which the same subsequently operate during elevating and low-

ering movements of the awning. The spring within the curtain roller 7, serves to wind the awning fabric thereon when it is desired to elevate the awning in a usual and well known manner, the cord 14, winding therewith, and when it is desired to lower the awning, the cord 14, is pulled downwardly, thus rotating the curtain roller 7, against the stress of its internal spring. The U-bracket 9, is adapted to slide downwardly by gravity in the guides 5, finally striking the Z- or angled brackets 12, therein and swinging outwardly into a substantially horizontal position after which the cord 14, is engaged over the hook 17, on said U-bracket and fastened to the sill of the window to hold the awning in extended position.

The shape of the gudgeon heads 11, as clearly shown in Fig. 6, is such that when the U-bracket 9, is swung downwardly into horizontal position to extend the fabric away from the window, said gudgeon heads are disposed beneath the inwardly projecting ends 13, of the Z- or angle brackets 12, thus preventing the inner ends of said U-bracket 9, being forced upwardly by accident or otherwise within the guide channels 5. The cross brace rod 20, at the middle of the window frame, serves to confine a certain portion of the awning fabric inwardly near the window pane, but if it is desired to clean the window, said rod 20, may be readily swung into position out of use by merely moving the gravity retaining pawl 22, upwardly, and withdrawing the rod and allowing the same to swing downwardly alongside the window frame.

I am aware that various details of construction may be varied through a wide range without departing from the principles of this invention, and I therefore do not purpose limiting the patent granted otherwise than necessitated by the prior art.

I claim as my invention:

1. The combination with an awning mounted in a window frame, of a cross brace rod attached across the window frame to confine a portion of the awning in the plane of the window frame when the awning is lowered, and means permitting release of said rod to permit the same to swing downwardly alongside the window frame.

2. In a device of the class described the combination with an awning mounted on a window frame, of a notched bracket plate secured on the window frame, a cross rod having one end pivotally mounted on the window frame opposite said bracket plate, the other end of said cross rod adapted to removably seat in said notched bracket plate to hold the upper portion of the awning fabric in the plane of the window frame when the awning is lowered.

3. In a device of the class described the combination with an awning mounted in a window frame, of a notched bracket plate secured on one side of the window frame, a cross rod having one end pivotally secured on the other side of the window frame opposite said notched bracket plate, the free end of said cross rod bent at an angle and adapted to seat in said notched bracket plate to permit said cross rod to bear against the awning fabric to hold the upper

portion thereof in the plane of the window frame, and a pawl pivotally mounted on said notched bracket plate for locking the angled end of said cross rod in said plate. 15

In testimony whereof I have hereunto subscribed my name in the presence of two subscribing witnesses.

HARRY H. SCHROYER.
